UNITED STATES PATENT OFFICE.

MELVILLE CLARK, OF CHICAGO, ILLINOIS.

INTERIOR-PLAYER PIANO.

1,014,840.

Specification of Letters Patent. Patented Jan. 16, 1912.

Application filed May 12, 1909. Serial No. 495,440.

To all whom it may concern:

Be it known that I, MELVILLE CLARK, a citizen of the United States, residing at Chicago, in the county of Cook and State of Illinois, have invented new and useful Improvements in Interior-Player Pianos; of which the following is a specification, reference being had to the drawings forming a part thereof.

The purpose of this invention is primarily to provide a grand piano with automatic playing devices adapted for independently playing two parts of a piece of music, as a solo or melody and an accompaniment, and comprising for that purpose two pneumatic actions and tracker devices having ducts in different groups for connection with said actions respectively.

It consists in the features of construction shown and described as indicated in the claims.

In the drawings:—Figure 1 is a fore-and-aft vertical section of a portion of a grand piano equipped with this invention. Fig. 2 is an inverted plan view of the pneumatic actions. Fig. 3 is a section at the line 2—3 on Fig. 1. Fig. 4 is a section at the line 4—4 on Fig. 3.

The usual parts of a grand piano and its case are shown in the drawings, comprising the manual bed or base plank, A, above which the manual keys, B, are mounted in the usual manner. Between the framing timbers of the rear portion of the piano and supported thereby there are mounted the pumpers and retaining bellows substantially as shown in my Patent No. 876,438, dated January 14, 1908, and partly shown in the drawings, in which the retaining bellows, C and C', and one of the pumpers, D, are seen in Fig. 1. Under the manual breast of the instrument there is mounted the tracker board, E, and its connections and the roll carrying devices conventionally represented by the two rolls, F and F', all carried in a frame F' which is mounted for sliding in and out the slide-ways, a, under the base plank, A, of the instrument. The pneumatic actions are both mounted rearward of the harp or pedal support, represented as to position at G. The construction of the pneumatic actions is familiar and need only be indicated in general as comprising, in the principal action, four banks of motor pneumatics, H, connected with the primary chamber, H¹, of

said principal action, and three banks of motor pneumatics, J, of the supplemental action, mounted forward of the primary pneumatic chamber, H¹, of said supplemental action, and suitably connected in a familiar manner with the primary pneumatics, h, of said supplemental action. The motor pneumatics, H, of the principal action have their moving walls below their fixed walls, so that they collapse upward, and they are provided with upwardly striking pitmen, K, which extend through the base plank, A, for striking upwardly upon the rear ends of the manual keys, as clearly seen in Fig. 1. The motor pneumatics of the supplemental action are mounted with their moving walls above their fixed walls, so that they collapse downward; and said moving walls are connected by rods, m, stepped upon and connected to horizontal levers, M, which extend forwardly under both actions, being fulcrumed at m¹, upon a bar, M², carried by the action frames, M³, at a point about two-thirds of the length of the levers from their rear connections; and at the forward ends of said levers upwardly striking pitmen, N, are connected to them respectively, and extend up through the base plank, A, for operating upwardly upon the manual keys, B, upon which they act at a line forward of the pitmen, K.

The tracker device comprises a tracker board, E, having a series of ducts consisting of three groups, all of which are connected by flexible tubes, E¹, E² and E³, with a tracker duct board, E'. The ducts of the first group are connected by tubes, E¹, directly with the duct board, E', and thence by flexible tubes, P, for communication with the principal action. The ducts of the second group are connected by tubes, E², with the slide valve bar, S, hereinafter described, and thence by flexible tubes, P¹, leading from the duct board, E', for communication with the supplemental action; and the ducts of the third group are connected by tubes, E³, with the valve bar, S, and thence by two sets of tubes, P² and P³, leading from the duct board, E', for communication respectively with the principal action and the supplemental action for connecting the ducts of said third group alternately with either of said actions. The flexible tubes, P and P³, extend from the duct board, E', to the principal action, with which they are connected in the usual manner; said tubes being di-

vided into two masses grouped in the trunks, p , p , respectively, for passing around the harp or pedal support to reach the primary pneumatics of the principal action, where one of the tubes is distinctly shown in Fig. 1 connected in a manner which will be well understood as illustrating the connection of the entire number comprising both said groups, P^1 and P^2 . The flexible tubes, P^1 and P^2 , extend to the supplemental action, being divided into two masses which are grouped respectively in the trunks, p , p , for passing by the harp or pedal support, and thence in the subordinate trunks, p^1 , p^1 , for passing by the ends of the principal action to reach the primary pneumatics of said supplemental action, with which one of said ducts is shown connected in Fig. 1 in a manner which will illustrate the connection with the remainder. The tubes, P^1 , lead to the primary pneumatics at the end portions of the supplemental action, and the tubes, P^3 , lead to the primary pneumatics of the intermediate portion of said action, as seen in Fig. 2. As stated, the tubes, P^1 and P^3 , are connected to the duct board, E^x , on which the valve bar comprising two members, S , S , is mounted, for registration of their ports with the corresponding ports of said duct board, and adapted to be moved for non-registration of said ports for cutting off communication thereof with the supplemental action. The tubes, P^2 , are also connected with the duct board, E^x , as stated, the ports of the corresponding tubes of the valve bar which communicate with the ports of said tubes, P^2 , being positioned in the face of the valve bar which bears upon the duct board so as to be in registration with the corresponding duct board ports when the valve bar is moved longitudinally for non-registration of the ports connected with the tubes, P^1 and P^3 , the valve bar having a range of movement from the position of registration of the ports of the tubes, P^1 and P^3 , to the position of registration of the ports of the tubes, P^2 , adequate for an intermediate position at which all the ports of the bar are out of registration with the corresponding ports of the board, that being the position in which the parts are shown in Figs. 3 and 4, from which figures it will be understood that movement of the valve bar, S , to the right will bring the ports of the tubes, E^2 , into registration with the ports of the tubes, P^1 , and the ports, E^3 , into registration with the ports of the tubes, P^3 ; and movement to the left will bring the ports of the tubes, E^2 , into registration with the ports of the tubes, P^2 , while the ports of the tubes, E^2 , are cut off from registration with the ports of the tubes, P^1 . The two members, S , S , of the valve bar are connected together for movement as a unitary structure by a rigid yoke piece, s ; and a le-

ver, S^1 , which is mounted in position for manipulation by the operator engages the valve bar in any convenient manner for adjusting the latter to either of the three positions indicated.

The supplemental action is designed for playing any part which is to be distinguished, or playing any part which is to be made prominent with respect to any other part, as for playing the melody more prominently than the accompaniment with which it is associated; and for that purpose, the supplemental action is designed to operate upon the manual keys more forcibly than the principal action. This is in part effected by the disposition of the several elements and the proportions of the lever connections of the motor pneumatics of the supplemental action to the manual keys; the motor pneumatics of the supplemental action are deeper and have a longer stroke than those of the principal action,—only three banks of pneumatics in the supplemental action being provided in a space equal to that which accommodates four banks of the principal action. This deeper stroke is accommodated, as will be noticed, by the proportions of the two arms of the levers, M , the rear arm connected with the pneumatic being double the length of the forward arm connected with the pitmen, so that the full value of the extra depth of the motor pneumatic for producing a forceful stroke is obtained by the shortened stroke of the forward end of the lever operating by means of the pitmen upon the key nearer to its fulcrum. But for further and more marked distinction between the force of the two actions upon the keys, it is preferred to provide for operating the pneumatic of the supplemental action from an air chamber exhausted to a higher degree than that from which the principal action is operated. For that purpose the principal action is connected by an air trunk, c^1 , with the low tension chamber of a bellows, C^1 , and the supplemental action is connected by an air trunk, c , with the high tension chamber of the bellows, C , both said bellows being connected with the pumpers, D , in a manner needing no further description. I do not exclude means for changing these connections; and such means are fully described in my application Serial No. 488,625, filed April 8, 1909 (Patent No. 1,009,828, Nov. 28, 1911), but for the purpose of the present application it may be understood that the principal action would be generally connected with the low tension and the supplemental action would be generally connected with the high tension.

I claim:

1. In a piano, in combination with the manual keys, a principal pneumatic action and a supplemental pneumatic action for

operating independently of each other upon the manual keys at the same side of their fulcrums, the motor pneumatics of one action being rearward of those of the other, 5 the strikers of both actions being located forward of the foremost group of motor pneumatics; horizontal levers from the rear group of motor pneumatics extending past the forward group to the strikers, such levers being fulcrumed intermediate their ends and nearer to the striker connections than to the pneumatic connections.

2. In a piano, in combination with the manual keys, a principal pneumatic action and a supplemental pneumatic action for operating independently of each other upon the manual keys, both actions being positioned below the keys for action upwardly thereon rearward of their fulcrums, the motor pneumatics of one action being rearward of those of the other, and the strikers of both actions being located forward of the foremost group of motor pneumatics; horizontal levers from the rear group of motor pneumatics extending past the forward group to the strikers, such levers being fulcrumed intermediate their ends and nearer to the striker connections than to the pneumatic connections.

3. In a piano, in combination, the manual keys, principal pneumatic action and a supplemental pneumatic action for operating independently of each other upon the manual keys, both actions being positioned below the keys for action upwardly thereon rearward of their fulcrums, the motor pneumatics of one action being rearward of those of the other, and having its strikers forward of those of the other, the strikers of both actions being forward of the forward group of motor pneumatics, and levers from the rear group of motor pneumatics extending to the forward set of strikers, said levers being fulcrumed between their ends and nearer to the striker connections than to the pneumatic connections.

4. In a piano, in combination with the manual keys, two pneumatic actions for operating independently of each other upon the keys; a tracker device mounted under the manual and adapted to be adjusted to a position forward of the manual breast of the instrument, comprising three groups of ducts, one for connection with the principal action, a second for connection with the supplemental action, and a third for connection with both actions; a duct board and a valve bar thereon, one of said elements having a set of ports connected with the tracker board ducts of the second and third groups, the other element having a set of ports for registration with both said groups of the first mentioned element, and another set of ports for registration with the ports of said first mentioned element of the third group

only, one of said two elements being movable upon the other to three positions, at one of which the first set of ports of said second element registers, as stated, and at another of which the second set of ports of 70 said second element registers as stated, and at the third of which neither of said sets registers; flexible tubes leading from the supplemental action to said second element connected thereto at said first set of ports, 75 and flexible tubes from the principal action leading to said second element and connected thereto at said second set of ports.

5. In a piano, in combination with the manual keys, two pneumatic actions for operating independently of each other upon the keys; a tracker device mounted under the manual and adapted to be adjusted to a position forward of the manual breast of the instrument, comprising three groups of 80 ducts, one for connection with the principal action, a second for connection with the supplemental action, and a third for connection with both actions; a duct board and a valve bar thereon, one of said elements having a set of ports connected with the tracker board ducts of the second and third groups, 85 the other element having a set of ports for registration with both said groups of the first mentioned element, and another set of 90 ports for registration with the ports of said first mentioned element of the third group only, one of said two elements being movable upon the other to three positions, at one of which the first set of ports of said second element registers, as stated, and at another of which the second set of ports of said second element registers as stated, and at the third of which neither of said sets registers; flexible tubes leading from the supplemental action to said second element connected thereto at said first set of ports; flexible tubes from the principal action leading to said second element and connected thereto at said second set of ports, and means for 95 moving said two elements to shift said registration.

6. In a piano, in combination with the manual keys, two pneumatic actions for operating independently of each other upon the keys; a tracker device comprising three groups of ducts, one for connection with the principal action, a second for connection with the supplemental action, and a third for connection with both actions; a duct 110 board and a valve bar thereon, one of said elements having a set of ports connected with the tracker board ducts of the second and third groups, the other element having a set of ports for registration with both 115 said groups of the first-mentioned element and another set of ports for registration with the ports of said first-mentioned element of the third group only, one of said two elements being movable upon the other 120

to three positions, at one of which the first set of ducts of said second element registers as stated, and at another of which the second set of ports of the second element registers 5 as stated, and at the third of which neither of said sets registers; flexible tubes leading from the supplemental action to said second element connected thereto at said first set of ports, and flexible tubes from the principal action leading to said second element and connected thereto at said second set of ports.

7. In a piano, in combination with the manual keys, two pneumatic actions for operating independently of each other upon the keys; a tracker device comprising three groups of ducts, one for connection with the principal action, a second for connection with the supplemental action, and a third 15 for connection with both actions; a duct board and a valve bar thereon, one of said elements having a set of ports connected with the tracker board ducts of the second and third groups, the other element having 20 a set of ports for registration with both 25

said groups of the first-mentioned element and another set of ports for registration with the ports of said first-mentioned element of the third group only, one of said two elements being movable upon the other 30 to three positions, at one of which the first set of ducts of said second element registers as stated, and at another of which the second set of ports of the second element registers as stated, and at the third of which neither 35 of said sets registers; flexible tubes leading from the supplemental action to said second element connected thereto at said first set of ports, and flexible tubes from the principal action leading to said second element and connected thereto at said second set of ports, and means for moving said two elements to shift said registration.

In testimony hereof, I have hereunto set my hand at Chicago, Illinois, this 8th day of May, 1909.

MELVILLE CLARK.
